CLAIM

The ornamental design for a soap dispenser refill adapter, as shown and described.

DESCRIPTION

FIG. 1 is a top front perspective view of a soap dispenser refill adapter showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The darker broken lines in the figures depict boundaries of the claimed design. The lighter broken lines in the figures depict portions of the soap dispenser refill adapter that form no part of the claimed design.

1 Claim, 4 Drawing Sheets
